UNITED STATES PATENT OFFICE.

JULIUS A. DYBLIE, OF ANACONDA, MONTANA.

APPARATUS FOR IMMERSING CASTINGS.

SPECIFICATION forming part of Letters Patent No. 628,241, dated July 4, 1899.

Application filed October 6, 1898. Serial No. 692,802. (No model.)

To all whom it may concern:

Be it known that I, JULIUS A. DYBLIE, a citizen of the United States, residing at Anaconda, in the State of Montana, have invented 5 certain new and useful Improvements in Apparatus for Immersing Castings, of which I do declare the following to be a full, clear, and exact description, reference being had to the accompanying drawings, forming part of 10 this specification.

In forming wire bars, ingots, plates, and like castings of refined copper it is important that as soon as the copper reaches a certain temperature after being cast it should be immersed in water in order to arrest oxidation. 15

The present invention has for its object to provide a simple and effective apparatus whereby wire bars, ingots, plates, or like castings of copper may be immersed; and the invention consists in the novel features of construction hereinafter described, illustrated in the accompanying drawings, and particularly pointed out in the claims at the end of this specification.

25 In the accompanying drawings I have shown my improved apparatus used in connection with a tilting furnace and ladle. This furnace and ladle do not, however, form subject-matter of the present application, being specifically claimed in an application executed 30 and filed by me of even date herewith.

Figure 1 is a plan view showing my improved apparatus arranged each side of a ladle-crane and in front of a tilting furnace. 35 Fig. 2 is a plan view of my improved immersing apparatus, the table that carries the molds being removed. Fig. 3 is a view in vertical cross-section on line 3 3 of Fig. 5. Fig. 4 is a view in side elevation of my improved apparatus. 40 Fig. 5 is a view in vertical longitudinal section. Fig. 6 is a view of the discharge end of the apparatus. Fig. 7 is a view in side elevation of the discharge end of the apparatus. Fig. 8 is a view in vertical cross-section 45 on line 8 8 of Fig. 4. Fig. 9 is a plan view of part of the mold-carriage. Fig. 10 is a view in cross-section on line 10 10 of Fig. 9. Fig. 11 is a view in central vertical section through the drum at the discharge end of the 50 apparatus. Fig. 12 is a view in vertical section through the friction clutch-drum on the mold-shafts, parts being shown in side elevation. Fig. 13 is an end view of the parts in Fig. 12. Fig. 14 is a view in horizontal section

through the parts shown in Figs. 12 and 13, 55 the section being taken below the friction-drum.

Referring to the accompanying drawings, A designates the tilting furnace.

B designates the hydraulic cylinder where- 60 by the furnace is operated, and C designates the hydraulic crane that carries the ladle C', into which the molten metal will be received from the furnace A.

In Fig. 1 of the drawings my improved ap- 65 paratus for immersing the castings is shown at each side of the ladle-crane. This arrangement is preferable, particularly where large castings are made, since in making such castings a little time is required for them to set 70 before being dumped into the water, and the use of the immersing apparatus upon both sides of the ladle-crane enables the casting operation to proceed without interruption.

My improved immersing apparatus com- 75 prises a tank D, adapted to contain water, and lengthwise of this tank at a distance from its bottom extend the cross-beams d, upon which rest longitudinal I-beams d', that support the table E. The table E is preferably connected 80 to the side walls of the tank D by means of the angle-plates e. Along the bottom of the tank D is also preferably extended a series of cross-bars f, the ends of which rest upon angle-bars f', secured at the bottom corners 85 of the tank, and upon the cross-bars f extend the longitudinal bars f², on which the carrier-bars g of the conveyer will travel. These carrier-bars g are arranged at convenient distances apart and are preferably 90 formed of angle-bars, as shown, the ends of these bars being attached to certain links of the carrier-chains G, that pass over sprocket-wheels h and h', that are mounted, respec- 95 tively, on the shafts h² and h³ at the opposite ends of the tank D. The shaft h³ is located about midway between the top and bottom of the tank at one end, while the shaft h² is located adjacent to the top of the tank at its opposite or discharge end, and upon the shaft 100 h² are keyed suitable wheels h⁴, carrying a drum H, over which the castings will pass as they are carried outward up the raised discharge end of the false bottom E. A discharge-table K is supported by suitable 105 brackets at the discharge end of the tank, the upper edge of this table extending in proximity to the periphery of the drum H.

To the sides of the tank D opposite the point where the false bottom E begins its upward inclination I prefer to mount the guide-rolls M, that are carried by hangers m, pivoted at 5 m' to the side walls of the tank. The upper ends of the hangers m are preferably connected by cross-bars m², the weight of these cross-bars, of the rolls, and of the hangers serving to normally hold the rolls in the position shown by Figs. 3 and 5 of the drawings. The object in pivotally sustaining the guide-rolls M is to enable these rolls to yield in case they are struck by castings, the arrangement being such, however, that as the castings 10 pass upward along the inclined false bottom the rolls will be returned by gravity to their normal position.

Motion is imparted to the shaft h², the sprocket-wheels h, and the conveyer-chains 20 G preferably by means of a gear-wheel 2, keyed to the end of the shaft h², this gear-wheel meshing with a similar gear-wheel 3, that is journaled on a stud-axle 4, projecting outwardly from the bracket 5, bolted to the 25 side of the tank D, and the gear-wheel 3 meshes with a pinion 6, that is loosely mounted upon a drive-shaft 7, journaled in suitable bearings beneath the discharge end of the tank. Upon the shaft 7 is keyed in manner 30 free to slide lengthwise of the shaft one member 8 of a clutch, the corresponding member 9 of the clutch being shown as formed integral with the gear-wheel 6. The clutch member 8 is formed with a peripheral groove to 35 receive a ring 10, to which is pivotally connected the yoke-shaped lower end of the shift-lever 11, this lever being pivotally connected, as at 12, to the upper end of the axle 4. The drive-shaft 7 revolves continuously, and 40 when it is desirable to transmit movement from this shaft to the conveyer within the tank the lever 11 will be shifted so as to cause the members 8 and 9 of the clutch to engage, as shown in Figs. 6 and 7 of the drawings.

45 Along each side of the tank D extend the rails or I-beams 15, that are bolted to suitable chairs 16, (see Figs. 4 and 8,) that rest upon the ends of the I-beams 17, that extend transversely beneath and support the tank D. On 50 the rails 15 are mounted grooved friction-rolls 18, the axles of which are preferably united by the side bars 19, and upon these friction-rolls 18 bear the rails 20 of the ingot truck or carrier. The rails 20 are preferably I-beams 55 extending at each side of the truck and connected at suitable intervals by the cross-beams 21 of the shape shown and having their ends formed with depending flanges 22, that are bolted to the ends of the rails 20, and with 60 flanges 23, that are bolted to the tops of the rails. Between the cross-beams 21 and upon the tops of the rails 20 are placed the bearings 25, wherein are journaled the ends of the mold-shafts P. Each of the mold-shafts is 65 shown as having connected thereto steel plates p, by which are carried the molds R. As shown, these molds are formed with flanges r, that are

united by bolts 26 to the plates p of the mold-shafts, suitable spacing-plates 27 being interposed when required between the flanges of 70 the mold and the plates p. Each mold-shaft is preferably constructed to carry two oppositely-disposed molds, the purpose of this arrangement being to better balance the mold-shafts, and thus facilitate their operation, 75 and, moreover, enable either mold to be used in the event the other mold should become broken. One end of each mold-shaft is formed with a squared or like portion to receive a turning-key 30, by which the mold-shaft can be conveniently manipulated, and upon each mold-shaft is fixed a friction-wheel S, over which passes the friction-strap s, one end of this strap being attached by a bolt 31 to a lug 32, projecting from a bracket-plate 80 33, (see Figs. 12 to 14,) while the opposite end of the strap s is formed with a loop that encircles an eccentric 34, the shaft of which is journaled in a projection 35 from the bracket-plate 33, this eccentric-shaft being formed 90 with a handle 36, whereby the eccentric may be manipulated. The purpose of the friction drum and strap is to enable the operator to readily control the movement of the mold-shaft as the castings are dumped into the water within the tank D, and manifestly by this means the mold-shafts can be easily turned by the operator grasping the turning-key 30 after he has thrown down the eccentric-handle to set the brake. 100

In order to retain molds R in proper position for receiving the charge of metal from the casting-ladle, I prefer to employ latch-plates T, that are pivotally connected, as at t, (see Fig. 9,) to plates t', bolted upon the 105 tops of the cross-beams 21. When the latch-plates T are in position, (shown in Fig. 9,) the molds will be securely held in vertical position; but when the molds are to be turned to discharge their contents the latch-plates T 110 will be thrown backward. The plates t' are by preference adjustably connected to the beams 21 to permit the latch-plates to be positioned with respect to molds of different sizes and shapes, one simple means of adjustment being a slot t² within the plate, through 115 which passes the retaining-bolt t³, whereby the plate is held in place.

The rails 15 at the sides of the tank D are shown as provided with end stops 40 to limit 120 the travel of the rollers 18. One of the rollers 18 is shown as provided with an extended axle w, fitted with a hand-wheel W, whereby the operator can readily effect the shifting of the rollers 18, and consequently of the mold-truck that is supported by such rollers. Preferably the roller 18, to the axle of which the hand-wheel W is attached, will be slightly 125 larger in diameter than the other roller, so as to insure the movement of the mold-truck 130 when the hand-wheel W is turned.

From the foregoing description the operation of my improved apparatus will be seen to be as follows, viz: After the metal within

the furnace A has been refined the furnace will be tilted so as to pour the molten metal into the ladle C'. The ladle-crane C will then be shifted so as to swing the ladle over one or the other of the mold-trucks and tank and the metal will be poured from the ladle C' into the molds R. The operator by manipulating the hand-wheel W will advance the mold-trucks to receive the charges from the ladle. When the metal within the molds is set to the desired extent, the operator by turning the key 30 will impart a half-revolution successively to each of the mold-shafts, thereby dumping the contents of the molds into the water within the tank D and onto the false bottom E of the tank. The carrier-bars g as they move over the false bottom E will engage with the castings (wire bars, ingots, and the like) and will advance them along the false bottom E in the direction of the arrow, Fig. 5, up over the drum H and onto the discharge-table K, from which they will pass on to suitable cars or trucks.

By providing tanks on each side of the crane it is obvious that the casting operation may be carried on continuously, since while the filling of the molds is proceeding at one tank the setting of the castings and dumping of the molds will occur at the other tank. It is obvious, however, that my invention may be practiced by the employment of a single tank, and while my present invention is more especially designed for immersing castings of refined copper it is manifest that the apparatus may be employed for other purposes without departing from the spirit of my invention. So, also, it will be readily understood that the details of structure above set out may be widely varied by the skilled mechanic and features of the invention may be employed without its adoption as an entirety.

The molds shown in the accompanying drawings are such as will be employed in making wire bars; but it will be understood that molds of other shapes and sizes can be substituted in making ingots, plates, and the like.

Having thus described my invention, what I claim as new, and desire to secure by Letters Patent, is—

1. In apparatus of the character described, the combination of a tank provided with a false bottom having an upwardly-inclined end, a conveyer within said tank and arranged to travel over and beneath said false bottom, and means for driving said conveyer.

2. In apparatus of the character described, the combination of a tank, means for delivering castings into said tank, a false bottom arranged lengthwise of said tank and having an upwardly-inclined end, a discharge-drum arranged at the discharge end of said false bottom, and an endless conveyer arranged to travel over and beneath said false bottom within said tank and adapted to carry castings therefrom.

3. In apparatus of the character described, the combination of a tank, a mold-carrier mounted above said tank and provided with a series of independently-revolvable molds and friction mechanism for controlling the revolution of said molds. 70

4. In apparatus of the character described, the combination with a tank having rails extending longitudinally thereof at its sides, of a mold carrier or support extending across 75 said tank and supported by said rails and provided with a series of revolvable molds, said mold-carrier being mounted in manner to be shifted lengthwise of said tank upon said rails.

5. In apparatus of the character described, the combination with a tank having rails arranged outside thereof and below its top, friction-rolls mounted to travel upon said rails, a mold-carrier comprising side rails resting 85 upon said rolls and united by cross-beams that extend over the top of the tank and individually-revolvable shafts journaled on said side rails and molds carried by said shafts.

6. In apparatus of the character described, 90 the combination of the tank, a mold-carrier mounted above said tank and comprising side rails united by cross-beams, a series of revolvable molds journaled on said side rails and suitable latch mechanism connected to said 95 cross-beams and adapted to engage said molds and hold them in position.

7. In apparatus of the character described, the combination of a tank, a mold-carrier above said tank, individual mold-shafts journaled in said carrier, and provided with extended ends, molds adjustably connected to said mold-shafts, a friction-wheel upon each of said mold-shafts, a friction-strap, and an eccentric for controlling said friction-strap. 100 105

8. In apparatus of the character described, the combination of a tank, a mold-carrier supported above said tank and provided with side rails, friction-rolls upon which said side rails are sustained, the axle of one of said 110 friction-rolls being provided with a hand-wheel or like means whereby the roll may be revolved in order to impart movement to the mold-carrier.

9. In apparatus of the character described, 115 the combination of a tank provided with a plate or false bottom having an upwardly-inclined end, a conveyer arranged to travel over said plate or false bottom and pivotally-supported rolls for holding said conveyer in position as it moves up the inclined plate or false bottom. 120

In witness that I claim the foregoing I have hereunto set my hand this 13th day of September, A. D. 1898.

JULIUS A. DYBLIE.
